UNITED STATES PATENT OFFICE.

WILLIAM H. SIMMONS, OF SYRACUSE, NEW YORK.

DESIGN FOR A HAME.

SPECIFICATION forming part of Design No. 23,148, dated March 20, 1894.

Application filed February 17, 1894. Serial No. 500,575. Term of patent 14 years.

To all whom it may concern:

Be it known that I, WILLIAM H. SIMMONS, a citizen of the United States, and a resident of Syracuse, in the county of Onondago and State of New York, have invented and produced a new and original Design for Hames, of which the following is a specification, reference being had to the accompanying drawings, in which—

Figure 1 is a side elevation of a hame showing my design. Fig. 2 is a transverse sectional view taken through the middle of the hame, on the line $x-x$ of Fig. 1.

The leading feature of my design consists of a hame having in cross section a broad rounded side, a narrow curved edge, and sloping or converging walls which join the narrow curved edge and the broad rounded side, as shown by the transverse sectional view, Fig. 2; and it further consists of longitudinal grooves or depressions in the converging sides of the hame, between the broad and narrow edges thereof, which grooves extend nearly the entire length of the hame and which gradually merge into the rounded ends of the hame, as shown by Fig. 1 of the drawings.

A indicates the broad rounded side or edge of the hame.

B is the narrow curved edge, and C, D, are 30 the sloping walls, as represented by Fig. 2. These walls C, D, converge from the broad rounded side A to the narrow curved edge B thereof, with which they are joined.

The hame has the usual longitudinal contour, with the straight middle part and the curved ends, and in the sloping walls C, D, of the hame I provide the longitudinal grooves or channels E that extend nearly the length of the hame and the ends of which 40 terminate flush with the surfaces of the hame near the curved ends thereof.

What I claim is—

The design for a hame herein shown and described.

In testimony whereof I herewith affix my signature in the presence of two witnesses.

WILLIAM H. SIMMONS.
